CLAIM

The ornamental design for a generator standby electric power mechanical interlock, as shown and described.

DESCRIPTION

FIG. 1 is a perspective view of a generator standby electric power mechanical interlock showing my new design;

FIG. 2 is a second perspective view thereof;

FIG. 3 is an exploded perspective view thereof;

FIG. 4 is a second exploded perspective view thereof;

FIG. 5 is a perspective view thereof, shown in environmental use; and,

FIG. 6 is a second perspective view thereof, shown in environmental use.

The broken lines shown represent unclaimed subject matter and form no part of the claimed design.
